UNITED STATES PATENT OFFICE

2,073,422

BUTTON

Joseph Komorous, Riverside, Ill., assignor to
 Parisian Novelty Company, Chicago, Ill., a corporation of Illinois

Application January 18, 1936, Serial No. 59,767

1 Claim. (Cl. 40—1.5)

My invention relates more particularly to devices for display purposes such as, and more especially, buttons, particularly celluloid covered buttons, bearing display matter, as for example advertising.

My more particular objects are to provide a device of the character stated of such construction that it will be more attractive to those wishing to use such devices; will be adapted, by easy manipulation, for assembly by the user for displaying any of several forms of display matter and for ready substitution of one form of display matter for another; and other objects as will be manifest from the following description.

15 Referring to the accompanying drawing:

Fig. 1 is a front face view of a button constructed in accordance with my invention.

Figure 2 is a rear face view of the same.

Figure 3 is a rear face view of the device with 20 the rear cover plate removed.

Figure 4 is a front view of the front section of the device.

Figure 5 is an enlarged broken sectional view 25 5 of the device, the section being taken at the line on Fig. 1 and viewed in the direction of the arrow; and

Figure 6, a fragmentary edge view of the device.

Referring to the particular illustrated embodiment of the invention which is in the form of a 30 button provided with means for attaching it to an object, such as for example of cloth, the button is formed of two separable front and back sections 10 and 11, respectively, of such form as to permit them to be readily assembled together 35 and disassembled, as desired, and a third section 12 interposed between the sections 10 and 11 and provided for displaying through the front face of the button any suitable display matter, such as for example, an advertisement.

40 The front section 10 is shown as comprising a rim 13 of relatively stiff material, as for example sheet metal, covered by a sheet 14 of transparent celluloid or other desirable material held in place by an outwardly and forwardly turned annular 45 flange 15 on the rim 13, the rim 13 and sheet 14 forming a disklike structure.

If desired, the rim portion 13 may be utilized 50 for the display of any suitable matter, such as for example, printed advertising, which preferably, however, would be displayed upon a ring 16 of sheet material, such as for example paper, which covers the face of the rim 13 and thus becomes interposed between the rim 13 and the celluloid sheet 14, the rim 13 in effect forming 55 a marginal frame for the central transparent

sight area thus provided by the portion of the clear celluloid sheet 14 registering with the central opening in the rim 13.

The section 11 is preferably formed of a sheet metal disk having a rim portion 17 terminating in 5 an outwardly extending annular flange 18 a portion of which is shown as offset rearwardly as indicated at 19, the rim 17 being of such diameter as to snugly telescope with the rim 13 and be held assembled therewith against accidental separation. The shape and size of the section 11 is preferably such, as shown, as to cause the non-offset portion of the flange 18 to bear against the back edge of the rim 13, when the disk section 11 it bottomed in the section 10 against the section 15 12.

As an example of a means for securing the button in place, as for example on a cloth object, a safety pin 20 is secured to the back face 20 of the disk section 11.

The intermediate section 12 is provided for the display through the large central sight area of the section 10, of any suitable display matter, such as for example a printed advertisement. The section 12 may be formed of sheet paper or any other suitable material and is preferably of disk form or slightly greater diameter than the diameter of the central sight area referred to, with radial tongues 21 extending outwardly therefrom which cause the marginal portion of the section 12 to be recessed and which serve to properly center the section 12 relative to the sight area upon assembling the sections 10 and 12 together and to afford means whereby the section 12 may be readily disassembled from the section 10 by inserting an improvised tool under the edge of one of the tongues 21 and prying the section 12 out of place.

By providing the device with the central sight area referred to and the separate section 12 any 40 desired selection of display matter may be rendered exposed to view at the front face of the button; and the provision of the frame-forming rim 13 permits of the displaying thereon, if desired, of any permanent display matter, such as 45 advertising, as shown.

The provision of the flange 18 affords a part 50 between which and the rim 13 a tool may be inserted for readily prying the sections 10 and 11 apart, the provision of the offset portion 19 of the flange 18 permitting the main portion of this flange to lie against the rim 13 while affording a space between the portion 19 and the rim 13 of such depth as to permit of the ready separation of the sections 10 and 11 by inserting a wide 55

range of comparatively blunt devices, such as a screw driver, into the space between the portion 19 and the rim 13 and prying these sections apart.

5 While I have illustrated and described a particular embodiment of my invention, I do not wish to be understood as intending to limit it thereto as the same may be embodied in other forms of structure and the structure shown may 10 be variously modified and altered without departing from the spirit of the invention. Thus, by way of example, the flange 18 may be unprovided with the offset portion 19 requiring the use of a comparatively sharp edge tool to separate the 15 sections 10 and 11, or, in the absence of the offset portion 19, the section may be made of such size and proportions that the flange 18 will be slightly spaced from the section 10 when the section 11 is bottomed in the section 10 to permit a com-

paratively blunt tool to be used to separate these sections.

What I claim as new and desire to secure by Letters Patent, is:

A device of the character set forth comprising 5 a rim portion having a front inwardly extending flange receding toward the rear of said rim portion, a flexible member in said rim portion bearing display matter exposed to view through the opening in the rim portion, and means holding 10 said member in place, said member having spaced apart projections at its marginal edge extending radially outwardly from points on said member adjacent the edge of said opening, whereby crinkling of the marginal edge of said flexible member 15 is avoided in the application of pressure applied by said means against the rear face of said member.

JOSEPH KOMOROUS.
